UNITED STATES PATENT OFFICE.

GEORGE W. HILLS, OF NEWTON, MASSACHUSETTS, ASSIGNOR TO THE
INVISIBLE ELEVATOR COMPANY, OF NEWARK, NEW JERSEY.

DESIGN FOR AN ELEVATOR FOR SHOES.

SPECIFICATION forming part of Design No. 25,242, dated March 10, 1896.

Application filed January 18, 1896. Serial No. 576,041. Term of patent 14 years.

To all whom it may concern:

Be it known that I, GEORGE W. HILLS, a citizen of the United States, residing in Newton, in the county of Middlesex and State of Massachusetts, have invented a certain new and original Design for Elevators for Boots and Shoes, of which the following is a specification, reference being had to the accompanying drawings, in which—

10 Figure 1 is a perspective view; Fig. 2, a longitudinal section, and Fig. 3 a cross-section on the line 3 3 in Fig. 2.

15 The leading features of my design are the longitudinally-sloping convex upper surface, slightly concaved transversely, and the hollow or cove at the lower part of one side.

The elevator is wedge-shaped, having its thick rear end semicircular in plan, while the thin forward edge is cut straight across. The

under face is flat or plane along the central portion, and is joined to the vertical sides and rear by curves of short radius. At the mid-length on one side the joining curve is of larger radius, producing a cove or hollow gradually diminishing in depth toward the front and rear and flowing smoothly into the adjacent surfaces, as shown.

I claim—

The design for an elevator herein shown and described.

In testimony that I claim the invention above set forth I have affixed my signature in presence of two witnesses.

GEO. W. HILLS.

Witnesses:

CHAS. E. SEARLE,
WM. B. WILSON.
